UNITED STATES PATENT OFFICE.

ARNOLD A. SCHWARTZ, OF CHICAGO, ILLINOIS.

DESIGN FOR A LAMP BRACKET.

Application filed December 7, 1925. Serial No. 15,676. Term of patent 3½ years.

To all whom it may concern:

Be it known that I, ARNOLD A. SCHWARTZ, a citizen of the United States, residing at Chicago, in the county of Cook and State of Illinois, have invented a new, original, and ornamental Design for a Lamp Bracket, of which the following is a specification, reference being had to the accompanying drawing, forming a part thereof.

Figure 1 is a fragmentary end elevational

view of a lamp bracket embodying my ornamental design, the balance of the ornamentation within the uncompleted outline being a repetition of the fragment shown; and

Figure 2 is a side elevational view of the article shown in Figure 1.

I claim:

The ornamental design for a lamp bracket, substantially as shown.

ARNOLD A. SCHWARTZ.
